WAX APPLICATOR

Reinhold C. Schmidt, Sr., Pittsburgh, Pa., assignor of one-third to Reinhold C. Schmidt, Jr., McKeesport, and one-third to Laura Olive Schmidt, Pittsburgh, Pa.

Application November 26, 1943, Serial No. 511,856

3 Claims. (CL 91—39)

The present invention relates to improvements in waxing devices and has for a primary object the provision of a wax applicator which is of generally improved design.

Another object of the invention is to provide a wax applicator constructed so that the wax is forced through minute perforations of an applying member so as to effect uniform distribution thereof.

A further object of the invention is the provision of a wax applicator in which the wax is forced through a foraminous member through the medium of a spring pressed plunger.

Still another object of the invention is the provision of a wax applicator of the aforesaid character which is relatively simple and durable in construction, efficient in use and which can be easily disassembled.

Other objects and advantages of the invention will become apparent as the description progresses.

In the accompanying drawing forming a part of this specification and in which like numerals are employed to designate corresponding parts throughout:

Figure 1 is a top plan view of the assembled device in position for use, and

Figure 2 is a side elevational view of the same partly in section.

Referring in detail to the drawing, wherein for the purpose of illustration is shown a preferred example of the invention, 10 designates a container body in the form of a cylindrical rigid shell having an annular outwardly projecting bead 11 at the bottom thereof. At diametrically opposed sides of the body 10 are provided a pair of radially projecting trunnions 12 disposed intermediate the top and bottom thereof.

On the trunnions 12 are pivotally disposed the outer eye elements 13 of a pair of curved complementary yoke or bale forming sections 14. The inner ends of the yoke sections 14 are formed with parallel shanks 15 tightly secured in a bore in the inner end portion of an elongated straight handle 16. Pivotally connected with this handle, at its inner end, is a hook member 17 having the body shank formed at one end with a right angular portion 18 extending through a transverse bore in the handle and having formed at its outer end a U-shaped hook 19 adapted to be fitted over the top of the body 10 to hold the handle at a predetermined inclination with relation to the body, so as to facilitate movement of the applicator.

At the bottom of the body shell 10 is disposed

an applying member 20 which may comprise an approximately round piece of fabric constructed to provide a porous or foraminous medium having perforations of a size suitable for the discharge of required quantities of wax for distribution thereof on floors and the like. This fabric is arranged so that a skirt portion encircles the lower part of the body 10 and is removably held thereon by a retaining band or ring 21 which may advantageously be resilient or elastic for slidable fitting on the body and coacts with the bead 11 to firmly retain the fabric in position. As shown to advantage at Figure 2, the fabric or distributing medium 20 bulges below the bottom 15 of the shell.

Slidably fitted within the body shell 10 for axial movement therein is a forcer 22 which may be in the form of a flat plunger disk having an annular groove 23 in the top.

Within the top of the cylindrical shell 10 is removably mounted a header member 24 in the form of an elongated rigid bar having the center portions transversely offset and having the ends slidably fitted in L-shaped slots 25 formed in diametrically opposed parts of the body. Thus, the bar 24 has a length substantially equal to the exterior diameter of the shell and is mounted in position by lowering the ends through vertical extensions of the slots and thereafter turned circumferentially to engage horizontal extensions thereof, as illustrated in Figures 1 and 2. On the upwardly offset center portion of the bar 24 is fastened, by screws 26, an upstanding knob 27 disposed centrally of the top portion of the container body. To the underside of the bar is securely connected an abutment member 28 in the form of a disk having the lower face recessed to provide a shallow circular seat depression 29, for a purpose which will be later described. The member 28 is rigidly secured to the center of the bar 24 by a screw 30.

Between the abutment member 28 and the plunger 22 is mounted a spiral tapering compression spring 31 having the upper reduced end of a diameter suitable for seating in the depression 29 of the abutment and the lower end of increased diameter disposed to engage the groove 23 in the top of the plunger disk.

During use, a charge of wax, denoted at 32 is forced downwardly against the bottom of the cover 20 by the compression action of the spring 31, the top of which is held in fixed position by the abutment 28 while the bottom bears against the slidably movable plunger 22. The spring 55 exerts compression sufficient to force the wax

through the minute perforations or pores of the cover at a rate sufficient to cause extrusion sufficient to enable uniform application by slide manipulation of the container through the medium of the handle upon a floor or other surface to be waxed. Thus, the wax will be extruded in predetermined quantity for efficient application as long as the header bar 24 is fastened in holding position on the container. This position will enable convenient and economical distribution of the wax.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. In a waxing device, a wax container open at the top and bottom and having an annular exterior bead about its bottom edge, a porous cover fitting over the bottom of the container and extending up over the bead, a ring member about the part of the cover above the bead and slideable toward the bead to clamp the material of the cover against the bead and between the ring and wall of the container, a header member removably fixed in the upper portion of the container, an abutment member on the header, a plunger slideable in the container, a spring disposed between the abutment member of the header and the plunger and acting upon the latter to force wax from the interior of the container through the pores of the cover, a handle pivotally connected with the container, and a hook attached to the handle and engageable with the container for holding the handle at a pre-

determined inclination with relation to the container.

2. In a wax applicator, a cylindrical container body, a porous cover enclosing the bottom end of the body, slideable clamping means for removably holding the said cover on the body, the body having diametrically opposed L-shaped slots located in the upper end thereof, a removable header bar mounted diametrically in the upper portion of the body with its ends engaged in the slots, an abutment member secured to and depending from the said bar, a plunger disk disposed to slide axially in the body, and a spiral spring mounted between the abutment and the plunger and adapted to exert pressure upon the plunger to force wax from the bottom of the container and through the pores of the said cover.

3. In a wax applicator, a cylindrical container body formed with diametrically opposed L-shaped slots in its top edge, a porous cover enclosing the bottom end of the body and extending up against the sides, means clamping the part of the cover extending up about the sides of the body for removably holding the said cover on the body, a removable header bar mounted diametrically in the slots in the upper edge portion of the body, an abutment member secured to and depending from the said bar, a plunger disk disposed to slide axially in the body, a spiral spring mounted between the abutment and the plunger and adapted to exert pressure upon the plunger to force wax from the bottom of the container and through the pores of the said cover, a handle having pivotal connection with the opposed sides of the body, and a hook pivotally connected to the inner portion of the handle and engageable with the container for releasably holding the handle at a working inclination with relation to the container.

REINHOLD C. SCHMIDT, SR.
